INVENTOR.
John S. Campbell
BY *John S. Campbell*
Jack Snyder
ATTORNEY

UNITED STATES PATENT OFFICE.

JOHN S. CAMPBELL, OF PITTSBURGH, PENNSYLVANIA.

CLEANING APPARATUS.

Application filed February 21, 1927. Serial No. 169,779.

My invention relates to a cleaning apparatus and important objects thereof are to provide a device of the character described which will greatly facilitate the cleaning of 5 ceilings, walls and floors; which includes a readily removable and reversible cleaning element and a conveniently detachable holder for the latter; and which embodies novel resilient means for automatically adapting 10 the cleaning element thereof to the surface of the work to be cleaned, and for imparting proper pressure to the cleaning element to effect the cleaning operation.

Further objects of the invention are to 15 provide a device of the type stated which is simple in its construction and arrangement, strong, durable and efficient in its use, conveniently operable, positive in its action, and comparatively inexpensive to manufacture.

With the foregoing and other objects in view which will appear as the description proceeds, the invention resides in the combination and arrangement of parts and in the 25 details of construction hereinafter described and claimed, it being understood that changes in the precise embodiment of the invention hereinafter disclosed can be made within the scope of what is claimed without departing from the spirit of the invention.

In the drawing wherein like numerals of reference designate corresponding parts throughout the several views:

Figure 1 is a rear side elevational view of 35 a cleaning apparatus constructed in accordance with the invention.

Figure 2 is a side elevational view thereof.

Referring in detail to the drawing 1 denotes an integrally formed holder constructed from sheet metal and comprising a back wall 2 provided with a pair of forwardly disposed side walls 3. The marginal outer edges of the side walls 3 are bent inwardly toward each other and constitute securing flanges 4 for detachably connecting the cleaning element 5 to the holder 1.

The cleaning element 5 preferably consists of an elongated piece of sponge rubber, which is normally substantially rectangular in transverse cross section. Each of the side walls of the cleaning element 5, is formed with an incision 6, which extends along the entire length and at the approximate center of the thickness of the cleaning element 5.

In securing the cleaning element 5 to the holder 1 the securing flanges 4 extend into

respective incisions 6 and engage the rear portion 7 of the cleaning element 5 which is compressed and jammed into the holder 1 for securing the cleaning element to the latter as clearly shown in Figure 2. The projecting or cleaning portion 5' of the cleaning element 5 which is disposed forwardly of the holder 1 is utilized for cleaning purposes, and when worn from use, the cleaning element 5 may conveniently be reversed in the holder 1 to provide a renewed cleaning portion. The projecting cleaning portion 5' of the cleaning element 5 preferably overlaps the side and end edges of the holder 1 to prevent potential injury to objects contacting with the apparatus during its use.

While the cleaning element 5, embodied in my invention is preferably constructed from sponge rubber, it will be obvious that any other cleaning element applicable thereto may be employed without departing from the spirit of the invention.

A pair of rearwardly disposed lugs, respectively indicated at 8 and 9, are disposed adjacent to respective ends of the holder back wall 2. The lugs 8 and 9 are stamped directly from the latter and extend in opposite directions relatively to each other, with the open sides thereof disposed toward respective ends of the holder 1.

A pair of resilient supporting arms respectively indicated at 10 and 11, connect the holder 1 with the operating handle 12. The rearward ends of the arms 10 and 11 are preferably joined together and are permanently fixed in the forward ferruled end 13 of the handle 12.

The forward ends of the arms 10 and 11 are spread apart from each other and are suitably formed as indicated at 14, to detachably engage and overlap respective lugs 8 and 9 of the holder 1.

The rearward end portion of each of the arms 10 and 11 is coiled to provide a resilient spring 15. The latter provide a resilient action for maintaining the securing engagement of the arms 10 and 11 with respective lugs 8 and 9, until manually detached therefrom.

Normally the arms 10 and 11 extend forwardly with a lateral spread, from the handle 12, but the action of the springs 15 will permit of the arms 10 and 11, together with the holder 1 and cleaning element 5 carried thereby, to be forced to extend rearwardly at right angles relatively to the

handle 12, as shown in dash lines in Figure 2, or to assume any angular disposition between such right angular disposition and their normal forwardly spread alignment.

- 5 This construction of the arms 10 and 11 will provide for the automatic adjustment of the cleaning element 5 to flatly engage the surface to be cleaned while exerting a resilient pressure to the cleaning element 5
10 that will greatly facilitate and expedite the cleaning operation.

What I claim is:

- 15 In combination a cleaning apparatus of the character described comprising a rectangularly shaped sheet metal holder including a back wall, a cleaning element removably mounted in said holder, said holder

provided with a pair of lugs stamped from the said back wall thereof and disposed adjacent to respective ends of said holder, an operating handle, a pair of supporting arms having their rearward ends permanently fixed in the forward end of said handle, the forward ends of said pair of arms detachably respectively engaging said pair of lugs, the rearward end portion of each of said pair of arms being formed to provide a spring for maintaining said pair of arms in engagement with said lugs, said spiral springs further permitting varied tensional adjustment of said carrier relatively to said operating handle.

In testimony whereof I affix my signature.
JOHN S. CAMPBELL.
